UNITED STATES PATENT OFFICE.

CHESTER F. LANSING, OF FAYETTE, OHIO.

BROOM-HOLDER.

SPECIFICATION forming part of Letters Patent No. 379,961, dated March 27, 1888.

Application filed April 19, 1887. Serial No. 235,407. (No model.)

To all whom it may concern:

Be it known that I, CHESTER F. LANSING, a citizen of the United States, residing at Fayette, in the county of Fulton and State of Ohio, 5 have invented a new and useful Improvement in Broom-Holders, of which the following is a specification.

My invention relates to an improvement in broom-holders; and it consists in certain novel 10 features hereinafter described and claimed.

In the drawings, Figure 1 represents a perspective view of my broom-holder. Fig. 2 is a plan view of the same. Fig. 3 is a perspective view of the broom-holder in position for 15 packing.

Referring by letters to the drawings, A represents the back piece of the holder, which may be made of wood or metal and of any shape desired.

20 B represents a plano-concave strip or block of wood or metal, with its concave side outward, and which, if made of metal, may be integral with the back piece, and if made of wood may be secured thereto by screws, nails, or bolts.

25 C represents the broom-support, which is made of a single piece of wire depressed at its center to form the convex bearing portion *a* against the block B, the ends of the wire beyond its central bearing portion being turned 30 into semicircular loops *b*, forming the folding arms to support the broom, said semicircular arms being arranged on the same horizontal plane and having the extremities of the wire separated at *d*, so as to permit the insertion 35 and withdrawal of the broom-handle. The wire support C is secured to the block B by two staples, D, driven into the block B, permitting the support C to move loosely in said staples, so as to be folded upwardly and rear- 40 wardly against the back piece, A, to allow the holder to be packed in a small compass.

E represents a hook which is inserted in the block B near the lower edge thereof, and which is adapted to turn loosely in its socket for the purpose of engaging the horizontal central section of the support C and holding it securely in place when the support C is in position to receive the broom, or to be turned aside parallel with the block B to permit the support to be folded upwardly and rearwardly against 45 the back piece, A, to be in position for packing. At the upper end of the said back piece, A, is an opening, F, for the purpose of suspending the entire holder upon a nail, hook, or screw inserted in a door, wall, or other structure. At the lower end of the back piece, A, 50 is a hook, G, to which a dust-pan may be hung.

The advantage of my invention is that it provides a suitable and convenient place at all times for the reception of the broom, and also 55 protects the broom when not in use, as it is supported with the brush upward on the wire support C, thus preventing the weight of the broom from resting on the brush, and thereby warping and misshaping the same and rendering 65 it unfit for use.

Having thus described my invention, I claim:

A broom-holder consisting of a back, A, the wire support C, pivotally mounted thereon and 70 having a bearing portion, *a*, and a hook or catch mounted on the back to engage the said bearing portion *a* of the support C, substantially as set forth.

In testimony that I claim the foregoing as my 75 own I have hereto affixed my signature in presence of two witnesses.

CHESTER F. LANSING.

Witnesses:

LOUIS O. BENNER,
LEMUEL GRISIER.
